UNITED STATES PATENT OFFICE.

ARTHUR J. KERCHER, OF BERKELEY, AND WILLIAM WESLEY HICKS, OF SAN FRANCISCO, CALIFORNIA.

ELECTRIC HEATER.

Application filed March 10, 1924. Serial No. 698,089.

This invention relates to a device operated electrically, for heating a space, such as a room or the like. More particularly, it relates to a heater in which the heat is imparted to the space to be heated, by the aid of currents of air passing over surfaces heated electrically. Such a convection type of heater is disclosed for example in a co-pending application, filed July 17, 1922, in the name of William Wesley Hicks, entitled Electric heater, and having Serial Number 575,543.

It is one of the objects of the present invention to improve in general the heater shown in the said co-pending case.

It is another object of the invention to increase the efficiency of such a heater by providing a comparatively long passageway for the air in the heater, the better to influence the air and to impart a greater quantity of heat thereto.

In heaters of this type, it is usual to provide heating elements comprising a column of refractory material, such as clay, upon which one or more heating coils are placed. Sometimes the column is hollow, to provide a vertical passage for the air to be heated. The coils have usually been so arranged as to be visible, and have been operated at some degree of incandescence so as to produce a pleasing effect. However, it is well-known that it is more efficient to operate the heater so that no glow at all is apparent. It is another object of our invention to provide heating units of such construction that only a minor part of the coils, forming the visible portions thereof, is operated at the relatively inefficient glowing temperature.

In the prior types of heaters referred to, the coils are supported in grooves located in the periphery of the hollow member, there being as many independent grooves as there are coils. In order to vary the intensity of the heating, sometimes one or more of the coils are entirely disconnected, leaving the others in a glowing condition. This produces the effect of dark and glowing sections of the coils alternated in the grooves, and is somewhat objectionable, since a more pleasing effect is secured by having all of the exposed portions glowing. It is thus another object of our invention to make it possible to expose only continuously glowing wires

independently of variations in the degree of heat supplied by the heater.

Our invention possesses other advantageous features, some of which with the foregoing will be set forth at length in the following description, where we shall outline in full that form of the invention which we have selected for illustration in the drawings accompanying and forming part of the present invention. Although we have shown in the drawings but one embodiment of our invention, we do not desire to be limited thereto, since the invention as expressed in the claims may be embodied in other forms also.

Referring to the drawings:

Figure 1 is an elevation of one of the heating elements, with some of the heating wires omitted, in order to show the structure more clearly;

Fig. 2 is a sectional view, taken along plane 2-2 of Fig. 1, and showing by the aid of dotted lines how the heating coils are supported, and how the refractory supports are held in place;

Fig. 3 is a sectional view, somewhat diagrammatic, of a complete heater embodying our invention; and

Fig. 4 is a fragmentary cross sectional view of the supporting column for the wire coils, and illustrates how the top of the column is constructed.

In the diagrammatic view of Fig. 3, a recess 11 is indicated in the vertical wall of a room or space, which recess serves to accommodate the heater. In order to permit the escape of convection currents of heated air from the device, a front cover or grille 12 is used, having perforations over at least part of its surface for the intake and escape of air from behind the grille 12.

Supported on back of the grille 12 is a hood or container 13 having a vertical wall and a horizontal shelf or extension 14 on which the heating units 15 are supported. At the top, the hood 13 curves over as shown at 16 to meet the rear surface of grille 12. The heating element 15 comprises in this instance, a hollow, rectangular column of refractory material, the faces of the column carrying helical coils arranged to be connected to a source of current. The details of the units will be explained at length in

connection with the other figures on the drawing; for the present it is sufficient to note that cool air may enter at the bottom from below the shelf 14, and pass through 8 apertures in this shelf into the hollow space in the column, and out at or near the top, impinging against the curved portion 16 of the hood, and thereby deflected outwardly from the grille.

10 A tortuous passageway is however provided for the air before it is permitted to escape in the manner just outlined, so that a comparatively long period of time may elapse before entry and exit, and a correspondingly large amount of heat taken up. The intake of cool air is effected near the bottom of the grille 12. A horizontal passageway 10 is provided therefor, formed by the two sheet metal hoods 17 and 18. 15 These hoods are similar in form to hood 13, but of progressively larger size, and each has a horizontal portion 19 or 20, leading to vertical walls which curve over as shown at 21 and 22. The three hoods may be 20 said to be nested. The outermost hood 18 has its curved portion 22 fastened to the rear surface of grille 12; but the curved portion 21 of the intermediate hood stops short of the grille, and leaves an open passageway 25 between the two passageways formed by the three hoods. That portion of grille 12 which is opposite this connecting passage- 30 wall 23 is imperforate, so as to prevent air from passing outwardly at that point. The same is true of the grille near the bottom between the two horizontal ledges or shelves 14 and 19.

The labyrinthine passageway for the air from inlet to outlet may now be traced. 35 From the horizontal portion 10, the air traverses the vertical passageway between the hoods 17 and 18; through the passageway 23; downward through the vertical passageway between the hoods 13 and 17; upwardly through the heating elements 15, and finally out near the top of the grille 12. Of course each of the hoods have side walls not shown, which also attach to the rear 45 surface of the grille; and furthermore, it is to be understood that as many elements 15 may be supported on the shelf 14 as desired.

Due to the fact that a long, tortuous path is traversed by the air in passing through the heater, it can take up a large 50 amount of heat produced by the elements 15. These elements impart heat to the various air passageways by radiation, convection and conduction, and the air in turn is heated by passing over these heated surfaces as well as near the hot conductors forming the active elements of units 15.

The construction of the heating units 15 is best disclosed in Figs. 1, 2, and 4. In 55 place of an integral hollow tube with helical grooves to support the heating coils 21

we provide in this instance separated and grooved vertical walls 25, which form sides of a rectangular or square column. One advantage of such an arrangement is that the coiled conductors 24 may be wound independently around each of the walls as indicated in the dotted lines in Fig. 2; and in this way, those conductors which are wound on the wall facing the grille or cover 12 can be independently energized to glowing temperature, while the others, which are not visible, can be more efficiently energized below glowing temperature. Thus the pleasing effect of glowing conductors is retained without material departure from maximum operating efficiency.

A further advantage resides in the fact that the walls 25, which are moulded from refractory material, such as clay, may be manufactured without cores and without any difficulty whatsoever in removing the pattern. It is to be noted that those portions of the grooves 26 which are on the exposed sides of the walls, are horizontal, the pitch being taken up in the inner face, as indicated in dotted lines in Fig. 1. This improves the appearance of the heater when in operation. Furthermore, the walls 25 in this instance are shown as provided with a continuous groove, forming the equivalent of a single pitched thread extending around the wall, and accommodating a coiled conductor. However, if desired, a plurality of grooves may be used to form multiple threads. Only part of the conductors is indicated in Fig. 1, the remainder of the grooves 26 on all walls being left unoccupied. The manner of insertion of the remainder of the conductors is evident, however, from the foregoing disclosure.

The ends of the conductors may be appropriately anchored in any manner.

The manner of supporting the walls on the shelf 14 may now be described. Clips 27 are stamped up from the shelf 14 to form 110 supports engaging the outside of the walls 25. Of course apertures 28 are left in the shelf 14 of the shape of the clips, which apertures are disposed exterior of the column formed by the walls, but these apertures are 115 helpful in permitting the air to escape from below the shelf 14 to the space above it. In somewhat similar fashion, clips 29 engaging the inner surfaces of the walls 25 are stamped out of shelf 14, in such manner that there is formed a rectangular aperture in this shelf, aligned with the axis of the column. In Fig. 2, the dotted lines 30 and 31 illustrate how the shelf is stamped before the clips 29 are bent up out of it to extend 120 perpendicularly thereto. Appropriate fastening devices, such as the bolts and nuts 32, may be provided for fastening the lower 125 ends of the walls 25 between the clips 27 and 29. Furthermore, enough space is left 130

near the corners of the column to prevent the conductors on adjacent walls from approaching too closely together, as well as to form passageways for the air to circulate freely around the heated conductors.

In order to increase the stability of the column supporting the heated wires, we preferably provide a cover plate 33 (shown most clearly in Fig. 4), which has a rectangular groove 34, alining with the top portions of the four walls 25. The cover 33, which is most readily made from sheet metal, also has its central portion 35 depressed, so as to form a double-walled groove near its periphery. Through this portion there extends a fastening bolt 36, which is long enough to pass down to, and through the horizontal shelf portion 19, as shown in Fig. 3. This bolt is tightened against the cover 35 and extension 19, so as to clamp the column formed by walls 25 tightly against the upper shelf 14.

We claim:

1. In a heating element, a flat refractory support having a groove extending around its periphery, said support having two opposite wide faces and two opposite narrow faces, and the groove forming a continuous thread around it, with horizontal portions only on one of the wide faces, and a coiled wire disposed in said groove.
2. In an electrical heating device, a plurality of supporting members made of refractory material, resistance conductors arranged on each of said supports, a plate, and means for supporting said members in the form of a group to define a central flue above said plate, said plate being cut away between opposed faces of said members to allow substantially unobstructed access of air to the flue from below the plate.
3. In an electrical air heater, a housing, electrical heating means normally maintained at glowing temperature for radiating heat disposed within the housing and adapted to be viewed thru one side thereof, and other electrical heating means operated

at a substantially lower temperature for heating by convection and disposed within the housing.

4. In an electrical air heater, a housing, electrical heating means normally maintained at glowing temperature for radiating heat disposed within the housing and adapted to be viewed thru one side thereof and other electrical heating means adapted to be heated to a non-glowing maximum temperature for heating by convection and also disposed within the housing.

5. An electrical air heater comprising a housing, electrical heating means normally maintained at a glowing temperature for heating by radiation disposed within said housing and adapted to be viewed thru one side of the housing, and other electrical heating means disposed within the housing in such a position as to produce substantially no effect upon the appearance of the heater as viewed thru said side, said latter means being operable at a non-glowing maximum temperature for heating by convection.

6. In an electrical heater, a housing, electrical heating means disposed within the housing and normally maintained at a glowing temperature for heating by radiation and adapted to be viewed from one side of the housing, and other electrical heating means disposed within the housing to the rear of said first means so as to produce substantially no effect upon the appearance of the heater, as viewed thru said side, said latter means operating at a non-glowing temperature for heating by convection.

7. In an electrical heater, a plurality of resistance units, certain of said units to be maintained at a glowing temperature for heating by radiation, the rest of said units to be maintained at non-glowing temperature for heating by convection.

In testimony whereof, we have hereunto set our hands.

ARTHUR J. KERCHER.
